UNITED STATES PATENT OFFICE

2,186,961

GAUGE FOR SHOE PRESSING MACHINES

Sidney J. Finn, Beverly, Mass., assignor to United Shoe Machinery Corporation, Borough of Flemington, N. J., a corporation of New Jersey

Application March 30, 1938, Serial No. 198,960

10 Claims.

(Cl. 12—33)

This invention relates to edge gauges and is particularly concerned with the provision of collapsible gauges adapted to engage and position the edge of a work piece, such as a blank of sheet material, which is to be subjected to pressure.

It is an object of the invention to provide a gauge for the above-mentioned purpose which will facilitate the accurate positioning, and maintaining in position, of a work piece, without danger of damage to itself, the work piece, or to pressure applying instrumentalities operating on the work piece even though such instrumentalities overlap the edge of said work piece and strike the gauge.

With this object in view the invention comprises a novel collapsible gauge which is normally sufficiently thick to be easily and definitely engaged by the edge face of a work piece, such for example, as a shoe sole, and the effective gauging face of which will not be deformed or displaced as the thickness of the gauge is reduced when it is subjected to pressure.

The invention is herein illustrated as embodied in an edge gauge for use in a sole attaching or laying machine, in connection with a welt hold-down device adapted to support or apply pressure to the welt or sole extension of a shoe. As shown, the gauge comprises a plurality of angularly disposed vanes or fingers of thin, resilient material the work engaging ends of which serve as an abutment against which to position the sole. When compressed by pressure applied in the direction of the thickness of the work piece, these vanes or fingers bend heightwise of the edge face thereof and flatten out as required by the pressure, thereby providing a gauge of reduced thickness and undiminished accuracy. The vanes or fingers may be made of spring steel and, in accordance with one embodiment of the invention, are arranged between a pair of parallel, yielding cover plates of the same material which facilitate the bending action of the fingers and prevent anything from being caught between their adjacent sides or edges. In accordance with another embodiment of the invention the gauge is made up of a plurality of thin resilient plates the work engaging edges of which are spaced apart but will move toward each other under pressure applied in the direction of the thickness of the work piece, thereby reducing the thickness of the gauge or abutment.

With the above and other objects and features in view, the invention will now be described in connection with the accompanying drawings and will thereafter be pointed out in the claims.

In the drawings:

Fig. 1 is a front elevation of the toe portion of a pad box, with parts broken away, showing the collapsible edge gauge of the present invention embodied therein;

Fig. 2 is a perspective view of the edge gauge with the top portion broken away to show details of construction;

Figs. 3 and 4 are views of the gauge similar to Fig. 1 illustrating its condition during different stages of the operation of applying pressure to the sole and shoe;

Fig. 5 is a plan view of the toe portion of the pad box showing the edge gauge abutting a sole in conjunction with a pair of collapsible side gauges for engaging the sole;

Figs. 6 and 7 are end elevational views of the edge gauge before and after it has been collapsed by pressure; and

Fig. 8 is a detail perspective view of one of the side gauges illustrated in Fig. 5.

The collapsible edge gauges of the present invention are illustrated herein as embodied in a cement sole attaching machine of the type disclosed in United States Letters Patent No. 2,047,185 granted July 14, 1936, on an application filed in the names of Milton H. Ballard et al., the machine being modified to include welt supporting or holdown mechanism of the type disclosed in Letters Patent of the United States No. 2,156,281, granted May 2, 1939, on an application filed in my name.

As disclosed in the patent first referred to, the cement sole attaching machine is provided with a plurality of pad boxes 10 each containing a yieldable pressure applying pad 12 upon which a previously cemented sole and shoe may be placed to receive sole attaching pressure. As indicated above, each pad box is provided with welt holdown mechanism 14 (Figs. 1 and 5) for supporting and pressing the welt of the shoe against the marginal portion of the outsole. Since this welt holdown mechanism is fully disclosed in my earlier patent only such portions thereof as are concerned with the present invention will be described herein. It should be understood that the edge gauges of the invention are not limited in their use to operating only upon soles and shoes or to embodiment in machines or pad boxes of the particular types illustrated herein.

As disclosed in my earlier patent, the pad box 10 carries near its forward end a toe piece 16 (Fig. 1) for engaging and supporting the welt at the toe end of the shoe, this toe piece being

detachably connected to the end of an arm 18 which, in turn, is pivotally mounted at 20 to a carrier member 22. The carrier member is arranged for pivotal movement laterally of the pad about a shoulder screw 24 threaded into a plate 26 which is adjustable longitudinally of the pad upon a slide 28 which supports the plate 26. The carrier member 22 has mounted in a suitable opening therein a disk 30 provided with a handle 32 and having an eccentric pin 34 extending downwardly into a slot in the plate 26 so that, when the handle 32 is rotated, the carrier 22 is swung about the pivot 24 to cause the toe piece 16 to be adjusted transversely of the pad. A screw 35 is provided for clamping the member 22 in adjusted position.

As also disclosed in the patent last referred to, the toe piece 16 is adjustable longitudinally of the pad by an adjusting screw 36 threaded into the plate 26 and having a groove 38 (Fig. 5) engaged by a fork member 40 secured by screws 42 to the slide 28, a set screw 44 being provided for holding the plate 26 in adjusted position.

The slide 28 is movable longitudinally of the pad 12 on stationary guideways 46 (Fig. 5) and this movement is effected by connecting the slide by a link 48 to the upper end of a lever 50 arranged to swing about a fixed pivot 52 (Fig. 1) and having a tail 54 which is engaged by a spring pressed pin 56 which tends to maintain the slide 28 and the toe piece 16 at the right-hand limit of their movement, as viewed in Figs. 1 and 5. The lower end of the lever 50 is connected by a screw 58 to a link 60 having a lost motion connection 62 to the lower end of a rocker member 64 forming a part of the sole attaching machine and fully disclosed in the Ballard et al. patent, the sole purpose of this last-described connection being to cause retraction of the toe piece 16 toward the toe end of the pad when the pressure applying mechanism of the machine is moved into its inoperative position. When the toe piece is retracted a small compression spring 66 (Fig. 1) acts upon a tail 68 on the arm 18 to raise the toe piece away from the surface of the pad, as illustrated in Fig. 1.

The slide 28, as shown in Figs. 1 and 5, has a projection or lip 70 extending from its forward or inner edge toward the rear end of the pad, this lip being so located that the longitudinal median line of a shoe mounted on the pad will bisect the lip widthwise. Secured by rivets 72 to the under side of the lip 70 is a collapsible edge gauge which forms a part of the present invention, this gauge being indicated generally in the drawings by the numeral 74 and being arranged in the present embodiment to engage the toe end of a sole. As best shown in Fig. 2, the edge gauge comprises a thin rectangular plate 76 substantially flat at its outer portion and separated at its inner portion by slots 78 (Fig. 5) into a plurality of thin vanes or fingers 80 (also referred to herein as plates) which are located side by side and are arranged to extend rearwardly toward the heel end of the pad 12. The plate 76 is formed of resilient sheet material such, for example, as spring steel, and the vanes or fingers 80 are bent or twisted during manufacture so that they are located at a substantial angle to the plane of the flat portion of the plate 76. The angle of the vanes may vary somewhat, if desired, but it is preferably such that the edges of the inner or operative ends thereof are located at about 45° to the flat portion of the plate. The original twisting of the vanes and their subsequent bending during operation is

facilitated by forming circular cutouts 82 at the rear or outer ends of the slots 78 and also adjacent to their forward or operative ends, by forming semicircular notches 80 on the outside edges of the two outer vanes, and by then removing the material between these cutouts and notches to decrease the width of the vanes between these points and thereby to reduce their resistance to bending during operation. The vanes are widest at their operative ends but these ends are narrow enough to prevent the adjacent edges thereof from striking against each other when the gauge is fully collapsed as hereinafter described.

The plate 76 is secured by the rivets 72 between a pair of substantially parallel cover plates 86, 88 formed of the same thin resilient material as the vanes and covering those members at their upper and lower sides or edges. Since the cover plates are composed of material which bends readily under pressure, the inner portions thereof, which overlap the inclined vanes, will be bent and spread apart, as best shown in Figs. 1 and 6, but will always remain in contact with the opposite edges of the vanes.

It will be understood from the foregoing that the edge gauge 74, constructed as described above, will present a work engaging end which is normally of sufficient thickness to be easily and definitely engaged by the edge face of the toe end of a sole A placed by an operator on the pad 12, thereby permitting the gauge to serve as an abutment for positioning the sole on the pad and maintaining it against displacement thereon. The gauge is yieldable in a forward direction by reason of the lever 50 and spring pressed pin 56 described above to permit the operator to locate the sole in the desired position lengthwise of the pad. When pressure is applied to the expanded portion of the gauge, that is, to the inner portions of either of the cover plates 86 or 88, the angularly disposed vanes 80 will readily bend between these cover plates to assume a position more nearly parallel to the plane of the sole and thus to cause the gauge as a whole to collapse or flatten out without danger of causing damage to itself, the shoe parts, the pad, or the pressure applying instrumentalities. As stated above, if the gauge is entirely collapsed by the pressure, the width and arrangement of the vanes forwardly of their operative ends prevents the adjacent edges of the vanes from striking or overlapping each other.

As disclosed in my earlier patent the pad box 10 carries a pair of upright stationary posts 90, 92 (Fig. 5) upon which are pivotally mounted for approximately horizontal swinging movement, a pair of arms 94, 96 which extend toward the heel end of the pad and have pivoted on their inner ends two side members 98, 100 of a welt support or holdown device, portions of the arm 96 and side member 100 being broken away in Fig. 5 to illustrate mechanism located below the welt holdown members. This lower mechanism comprises a pair of castings 102, 104 pivotally mounted on the upright posts 90, 92 and provided with ears between which are freely pivoted on horizontal pins 106, 108, respectively, side gauge carrying arms 110, 112. Secured by screws 114 to the carrying arms 110 and 112, respectively, are side gauges 116, 118 arranged yieldingly to engage or "find" the opposite edge faces of the sole A on the pad substantially at the tip line of the sole.

The side gauge 116 is illustrated in detail in Fig. 8 and comprises a plurality of thin plates or fingers the inner or operative portions of which curve abruptly in a direction to engage

5 a sole substantially at right angles to its edge face, these members being likewise composed of thin resilient material such as spring steel. As herein shown, three of these plates are utilized and they are secured together at their forward or outer ends, as viewed in Fig. 5, by the screws 114 which also hold each gauge as a unit to its carrier member. The fingers of each side gauge are also fastened together adjacent to their 10 curved portions by a spacing member 120 which is riveted to the plates and is provided with annular flanges or shoulders (not shown) extending between the plates so that, in addition to securing the three plates to each other, the spacing 15 member spreads or deflects the curved portions apart slightly, as shown in Fig. 8, and assists in maintaining these portions in this spaced relation so that the operative edges of the three plates together form a sole engaging abutment 20 of substantial thickness. In addition to the spacing member 120 the two outer plates of the gauge, as shown in Fig. 8, may be bent away from each other to produce the desired thickness at the operative end of the gauge. These side gauges 25 are arranged to engage the opposite edge faces of the sole A between the pad and the welt B of a shoe C, the welt holdown members 98 and 100 at opposite sides of the shoe supporting the welt in a flat position. Since the gauges are 30 formed of resilient material which yields readily under pressure applied in the direction of the thickness of the sole, they are capable of flattening out or collapsing under such pressure either from the welt B, the welt holdown members 35 or the pad. Moreover, they will collapse without danger of damaging the gauge or anything contacting therewith.

The carrier members 110 and 112 are pivoted freely on the pins 106, 108 so that the operative 40 end portions of the gauges 116, 118 normally rest by gravity on the surface of the pad 12. Since the surface of the pad is usually molded to conform closely to the curvatures of the bottom of the last upon which the shoe is mounted, the 45 parallel sole engaging edges of the gauges 116 and 118 will never be exactly parallel to the surface of the pad or to the plane of the sole resting thereon. Accordingly, there will be practically no danger of a thin sole passing between the spaced plates when the gauges are moved 50 into operative engagement therewith.

As disclosed in the Ballard et al. patent, the side gauges 116, 118 are moved inwardly yieldingly to engage the opposite sides of the sole by 55 a treadle (not shown) which moves a horizontal rod 122 (Fig. 5) located at the inner side of the pad box toward the right or heel end of the box. This rod swings the rocker member 64 (Fig. 1) in a direction to release the castings 102, 104, which are then being held in an inoperative position by the member 64, and to 60 permit compression springs 124, 126 (Fig. 5) to rotate these castings about the posts 90, 92 respectively, to move the gauges yieldingly against the sole. After the side gauges have contacted with the sole, further movement of the rocker member locks them in operative position by clamping mechanism 128, fully disclosed in the Ballard et al. patent and acting upon overlapping inner arms of the castings 102, 104, this clamping mechanism also acting to lock the slide 65 and the edge gage 74 in operative position.

After the side gauges 116 and 118 have been actuated and all three gauges have been locked 70 in position against the sole A, the shoe C is placed

thereon, the toe end of the shoe, as shown in Fig. 1, being first placed against the elevated toe piece 16 and then lowered with the toe piece until the shoe engages the sole in the proper lengthwise position, as shown in Fig. 3, the member 16 being at this time locked against forward movement by the clamping mechanism 128 referred to. When the shoe has been properly located both lengthwise and widthwise of the sole, the side pieces 98 and 100 of the welt holdown are brought into engagement therewith to support the side portions of the welt B of the shoe in the same manner that the toe piece 16 supports the toe end of the welt. It will be seen from what has been explained above that the three edge gauges 74, 116 and 118 will have now been subjected to pressure from the welt and the welt holdown members in the direction of the thickness of the sole because all of these members, as shown in Figs. 3, 4 and 5, extend beyond the edge face of the sole. The gauge 74 will at this time have been flattened out somewhat, as shown in Fig. 3, thereby permitting the welt to extend beyond the edge of the sole A in a proper flat position for permitting it to be cement attached to the sole. The same conditions will exist with respect to the side gauges, the welt and the sole edge at the side portions of the shoe, where the welt is supported by the side members 98 and 100 and bears against the side gauges 116, 118. 10 15 20 25 30 35 40 45 50 55 60 65 70 75

As fully disclosed in my earlier patent, the side members of the welt support are swung toward and from each other automatically by swinging movement of an upright swinging frame 130 (Fig. 5), this frame being connected by a rod 132 to a bell crank lever 134 which, in turn, is pivoted on the upright post 90 and has an outwardly extending arm 136 carrying an equalizing bar 138. The equalizing bar has depending pins engaging slots in the ends of a pair of arms extending toward each other from the opposite arms 94, 96. Accordingly, when the swinging frame 130 is moved forwardly into a substantially vertical operative position, the mechanism just described moves the side members 98 and 100 into engagement with the shoe, this movement being a yielding movement to accommodate shoes of different widths by reason of a spring 140 surrounding the rod 132. 50 55 60 65 70 75

The swinging frame 130 carries last and shoe engaging abutments (not shown) for pressing the shoe and sole against the pad 12 and it also carries a substantially horseshoe shaped pressing member for engaging the welt support or 60 holdown members 16, 98 and 100 and pressing them forcibly toward the pad, a fragment of this last-named member being indicated in the drawings by the numeral 142. Accordingly, after the sole and shoe have been mounted on the 65 pad and properly positioned thereon, and the swinging frame member has been pulled forwardly to move the welt holdown members 98 and 100 into engagement with the shoe, the power operated pressure applying mechanism of the machine will be actuated in the manner disclosed in the Ballard et al. patent to cause the abutments referred to, including the horseshoe shaped member 142, to descend toward the pad and apply the sole attaching pressure. Figs. 70 3, 4, 6 and 7 illustrate the manner in which the collapsible edge gauge 74 flattens out when the shoe is first placed on the sole and also when pressure is applied, as in Figs. 4 and 6, to attach the sole to the shoe. It will be observed in 75

Fig. 4 that when the full pressure is being exerted on the sole and shoe the yieldable pad 12 will be distorted and a portion thereof at the edge of the sole will bulge upwardly against the 5 lower side of the gauge, thereby causing the gauge to flatten out more than it would from downward pressure of the welt alone. Regardless of the pressure applied to the gauge by the welt or the distortion of the pad, however, the gauge 10 may continue to serve as an abutment as long as necessary for maintaining the sole in position on the pad without danger of damage to itself, the shoe parts or the pressure applying instrumentalities. When the pressure on the shoe 15 is relieved the collapsible gauges 74, 116 and 118 will, of course, return to their normal positions so that they may serve as abutments for engaging the edge face of the next sole to be operated upon.

20 Having thus described my invention, what I claim as new and desire to secure by Letters Patent of the United States is:

25 1. A gauge adapted to abut the edge face of a work piece and to engage said edge face throughout its extent in the direction of the thickness of the work piece, said gauge comprising a plate having a plurality of resilient fingers formed thereon normally twisted at angles widthwise of said edge face and being constructed and 30 arranged to bend under pressure applied in the direction of the thickness of the work piece and to flatten out toward a plane parallel to the plane of the work piece, and means for covering said fingers.

35 2. A gauge adapted to abut the edge face of a work piece and to engage said edge face throughout its extent in the direction of the thickness of the work piece, said gauge comprising a plurality of thin resilient fingers normally 40 inclined at angles widthwise of said edge face and being constructed and arranged to bend under pressure applied thereto in the direction of the thickness of the work piece and thereby to flatten out relatively to the work piece and 45 being also arranged to return to their original positions when the pressure is relieved, resilient means for covering said fingers, and means for securing the covering means in position relatively to said fingers.

50 3. A gauge for positioning the edge face of an object relatively to another object to be placed on the first object in overlapping relation to its edge face and pressed against said first object, said gauge comprising a plurality of resilient 55 vanes arranged in parallel relation to each other and normally inclined at angles widthwise of the edge face of said first object, said vanes being constructed and arranged to bend under pressure from the overlapping object in a direction that 60 reduces the thickness of the gauge as much as required by said pressure, the operative portions of said vanes being wider than the other portions thereof.

65 4. A gauge for positioning the edge face of a sole resting on a pad relatively to the periphery of a shoe to be placed on the sole in overlapping relation to its edge face and pressed against said sole, said gauge comprising a plurality of spaced 70 fingers having forward edges inclined to engage the edge face of the sole throughout its full extent heightwise of the sole, said fingers being arranged to flatten out from their inclined position under pressure from the overlapping shoe 75 as the shoe is placed on the sole and pressed

against said sole, and resilient plates arranged to cover the upper and lower sides of said fingers.

5 5. A gauge for positioning the edge face of a sole resting on a yieldable pad relatively to the periphery of a shoe to be placed on the sole in overlapping relation to the edge thereof and then pressed against the sole and pad, said gauge comprising a plurality of thin resilient fingers having sole engaging end portions of substantial height normally disposed at inclined angles to 10 the plane of the sole and providing an abutment of greater thickness than the sole for engaging the full thickness of the edge face thereof and positioning the sole on the pad, said fingers being constructed and arranged under pressure from 15 the shoe or the pad to bend and flatten out heightwise of the sole as much as required by said pressure and thereby to continue to serve as a gauge without damage to themselves, the shoe or the pad. 20

6. An edge gauge adapted to abut the edge face of a work piece throughout its full extent in the direction of the thickness of the work piece, said gauge comprising a plurality of thin resilient fingers disposed at angles widthwise 25 of said edge face and arranged to bend toward the plane of the work piece under pressure applied in the direction of the thickness of said work piece, thereby reducing the thickness of the gauge, and a pair of thin resilient plates located at opposite sides of said fingers and covering them, said plates being likewise arranged to bend toward the plane of the work piece under said pressure.

7. An edge gauge adapted to abut the edge 35 face of a work piece on a support and to position said work piece thereon, said gauge comprising a plurality of thin resilient fingers inclined at angles widthwise of said edge face and constructed and arranged to engage said edge 40 face throughout its full extent in the direction of the thickness of the work piece, and a pair of resilient plates located at opposite sides of said inclined fingers for covering said fingers, said fingers and plates being constructed and arranged to bend under pressure applied thereto in the direction of the thickness of the work piece and thereby to flatten out toward the plane of the work piece as much as permitted by the thicknesses of the materials forming the fingers 50 and plates. 45

8. In a machine for cement attaching soles to shoes, the combination of a pad for receiving a sole and a shoe which overlaps the edge face of the sole, a gauge for engaging the edge face of the sole on the pad, a member for locating the shoe relatively to the sole, and means for pressing the shoe against the sole, said sole gauge comprising a plurality of inclined resilient fingers constructed and arranged at their forward edges to engage the edge face of the sole throughout its extent in the direction of the thickness of the sole and to collapse under pressure applied heightwise of the sole as much as required by said pressure. 60

9. In a machine for applying pressure to shoe bottoms, the combination of a pad for supporting a sole and a shoe having a welt thereon arranged to overlap the edge face of the sole, a gauge adapted to abut the sole on the pad, said gauge comprising a plurality of inclined vanes enclosed between a pair of resilient plates and normally forming an abutment of greater thickness than the sole, a member for positioning the shoe relatively to the sole, and means for applying pres- 75

sure to the shoe and sole, said sole gauge being constructed and arranged under pressure from the shoe to collapse heightwise of the sole to a minimum thickness controlled by the thicknesses of the members forming the gauge.

10. A gauge for engaging the edge face of a sole on a pad and maintaining the sole in position relatively to a shoe placed thereon in overlapping relation to the edge of the sole and 10 pressed against said sole, said gauge comprising a series of substantially flat plates of thin resilient material secured together at one end and having edges at their opposite ends nor-

mally spaced apart in parallel relation to each other, said edges forming a sole engaging abutment of substantial thickness, said plates being constructed and arranged under pressure from the shoe or pad heightwise of the sole to bend toward each other as much as required by said pressure and thereby to cause the gauge to flatten out so that it may continue to serve as a gauge with undiminished accuracy and without danger of damaging itself or anything contact- 10 ing therewith.

SIDNEY J. FINN.
